UNITED STATES PATENT OFFICE.

SAMUEL W. REESE, OF CHICAGO, ILLINOIS.

IMPROVEMENT IN STENCIL-PLATES.

Specification forming part of Letters Patent No. **173,058**, dated February 1, 1876; application filed December 24, 1875.

To all whom it may concern:

Be it known that I, SAMUEL W. REESE, of Chicago, in the county of Cook and State of Illinois, have invented an Improvement in Adjustable Stencils of which the following is a specification:

The nature of my invention relates to an improvement in that class of stencil characters and letters which can be adjustably and interchangeably secured together in a right line, for marking names upon packages of merchandise; and it consists in a novel and peculiar means for locking the stencil-plates together, as more fully hereinafter set forth.

Figure 1 is a perspective view of a marking-plate composed of several stencil-plates joined together. Fig. 2 is a similar view of portions of the same detached. Fig. 3 is a longitudinal section of the same at *x x*.

In the drawing, A represents a stencil-plate having cut in it a letter character, in the usual

manner. The right-hand edge is turned over upon itself, and then again forward, forming a groove, *a*, for the left-hand edge *b*, which is flanged up to enter it, and for the purpose of preventing said edges from pulling apart, a bead is pressed or otherwise formed into said edges.

The upper corner of the forwardly-turned edge *a* is cut away, which facilitates the joining of the separate plates, as the flange *b* will meet and enter the groove *a* with more ease.

What I claim as my invention is—

The stencil-plate A, having the bead-shaped groove *a* at one end, and the bead-shaped flange *b* at the other, substantially as and for the purpose set forth.

SAMUEL W. REESE.
